CLAIM

The ornamental design for an anchor post with integral fastener for flexible line, substantially as shown and described.

DESCRIPTION

FIG. 1 is a front elevation view of an anchor post with integral fastener for flexible line showing my new design;

FIG. 2 is a top view taken on line 2—2 of FIG. 1;
FIG. 3 is a sectional view taken on line 3—3 of FIG. 2;
FIG. 4 is a partial rear elevation view of the design shown in FIG. 1.
